RELAY SELECTOR CIRCUIT ARRANGED TO
SIMULTANEOUSLY TEST A SELECTED
GROUP OF TRUNKSHarlan E. Grimes, Bromley, Ludlow Station, Ky.,
assignor to Automatic Electric Laboratories,
Inc., Chicago, Ill., a corporation of Delaware

Application January 30, 1946, Serial No. 644,339

11 Claims. (Cl. 179—18)

1

The present invention relates in general to telephone systems and in particular to an improved selector circuit for use therein.

Of the many telephone systems which have been invented, the Strowger step-by-step system has proved to be the most popular and most widely used. It is believed this is largely due to the high degree of reliability and simplification of maintenance problems which results from the use of a minimum amount of common equipment. Many systems have been invented which use relays as the sole switching means, the object being to reduce the degree of maintenance required to a minimum and to simplify maintenance by reducing the number of types of switching mechanisms employed. In such all-relay telephone systems the advantages of the Strowger unit construction can easily be retained in small exchanges of several hundred lines or less. For larger systems it has heretofore been necessary to resort to common control circuits with the attendant disadvantages of reduced reliability and increased maintenance difficulty due to the complexity of the circuits. While these larger systems could theoretically employ all-relay selectors which would function in an identical manner to the well-known Strowger switch, such operation is considered impractical as relay chains generally cannot hunt for an idle trunk in a group thereof at as high a rate of speed as a mechanical switch. Fast trunk hunting is essential in a step-by-step system to insure the extension of a connection from one switch to an idle switch in a succeeding group between the dialing of successive digits by the calling subscriber.

It is accordingly an object of the present invention to provide a self-contained relay-type selector which is arranged to test all trunks in a selected group simultaneously and to establish connection with an idle one thereof.

The invention has been illustrated in the form of a schematic diagram in the accompanying drawing. It comprises a selector having a plurality of group selecting (tens) relays each of which is operative to connect an associated group of trunks to a group of individual selecting (units) relays. A group of control relays and an impulse counting device are provided for selectively operating the group selecting relays in accordance with a series of digital impulses received over a calling subscriber's line. When a desired one of the group selecting relays has been operated, the individual selecting relays test all of the trunks in the selected group simultaneously and extend the calling line to an idle one thereof.

Referring now to the drawing, there is illustrated a calling subscriber's substation A which is connected to the incoming conductors L₁, L₂ and C of the selector via a line switch, or the equivalent, shown in block form. Following con-

2

ventional step-to-step practice, the selector has access to ten groups of trunks, each group including ten trunks. Each trunk terminates in a connector of which one is shown in block form. Each connector usually has access to one hundred subscriber's lines, all of the connectors in a group having access to the same lines.

When a subscriber at substation A raises the handset from the hookswitch to initiate a call, the line switch searches for an idle selector. Assuming that the selector illustrated is the first idle one found by the line switch, it extends the calling line to conductors L₁ and L₂ and extends ground over conductor C. The connection of the subscriber's loop between conductors L₁ and L₂ causes relay 110 to operate and close a circuit to relay 120 at contacts 111. The ground extended over conductor C completes a circuit through chain contacts, such as U₁c, on relays U₁ to U₀; off-normal contacts 162; relay 130; and chain contacts, such as U₁b, on relays U₁ to U₀ to battery. Relay 130 operates and grounds a supervisory lead at contacts 131 to provide an alarm in case dialing does not commence within a given time. Relay 120 operates and places a multiple ground on conductor C at contacts 121. The ground initially extended over this conductor from the line switch is subsequently removed.

The operating ground for relay 110 is obtained over conductor DTG which is connected to ground through a winding of a dial tone transformer, not shown. The dial tone is transmitted to the calling party to indicate that the exchange equipment is prepared to receive impulses. When the calling subscriber operates the calling device the circuit to relay 110 is interrupted a number of times corresponding to the first digit of the called party's number. Each time that relay 110 restores it closes a circuit from ground through contacts 111, 103, 122 and 142 to the stepping magnet 160 of the minor switch MS; and closes a circuit from ground through contacts 112 and 123, relay 130, and contacts such as U₁b on relays U₁ to U₀ to battery. The stepping magnet 160 advances the minor switch wipers W₁ and W₂ one step each time its circuit is completed by the restoration of relay 110. On the first step the off-normal contacts 162 and 163 are operated. The contacts 162 open the initial operating circuit to relay 130 which is thereafter held by the intermittent completion of its circuit at contacts 112. Both relays 120 and 130 are rendered slow-to-release by means of copper sleeves so that they will remain operated during impulsion.

At the end of the series of impulses relay 110 will remain operated, thereby causing relay 130 to restore after a brief delay. When relay 130 restores it closes ground through wiper W₂, contacts 125 and 132, relay 150, and contacts such as U₁b on relays U₁ to U₀ to battery; and closes

ground through wiper W2, contacts 133, and wiper W1 to the selected one of the tens relays T1 to T0. Assuming that wiper W1 had been advanced to the tenth step, relays T0 and 150 operate to extend the test conductors of trunks 01 to 90 to the lower windings of relays U1 to U0, respectively, through contacts such as T0c and 151. If these trunks are in use the test conductors are grounded, but when they are idle resistance battery is connected to the test conductor. One side of the lower winding of relay U1 is connected to ground through contacts 121 while the corresponding side of the lower windings of each of the succeeding relays U2 to U0 are connected to the same ground through break contacts, such as U1c, on each preceding relay. As there may be a number of trunks which are idle, several of the relays U1 to U0 may operate simultaneously. The lowest numbered relay to operate will close a locking circuit to its upper winding from ground through break contacts such as U1c on all of the preceding relays, its own make contacts such as U2c, and break contacts such as U1c on all of the preceding relays to battery. The lowest numbered relay to operate opens the operating and locking circuits to all of the succeeding relays at contacts such as U2c and U1b, respectively. The operation of contacts such as U2b also opens the circuit to relay 150 causing it to restore.

Assuming that the first trunk in the "0" group is idle, relay U1 operates, closes a circuit from ground through wiper W2 and contacts 133 and U1a to relay 100; and grounds the test conductor of trunk 01 at contacts U1c through contacts T0c to mark it busy. Relay 100 operates and switches the calling line through to the 01 connector at contacts 101 and 102 through contacts T0a and T0b. Relay 110 restores and opens the circuit to relay 120 at contacts 111. Relay 120 restores after a brief delay and removes a multiple ground from the control conductor C at contacts 121 (by this time the succeeding connector switch will have grounded the control conductor). The connection is extended to the called party B by the connector under the control of the calling party in the usual manner.

When the conversation has been completed and the calling party disconnects, the connector removes ground from the test, or control, conductor of trunk 01 thereby opening the locking circuit to the upper winding of relay U1. Relay U1 restores and opens the circuit to relay 100 at contacts U1a. Relay 100 restores; closes a circuit from ground through contacts 111, 103, 122, 143 and 163 to the minor switch release magnet 161; and closes ground through wiper W2, contacts 125 and 104, and the upper winding of relay 130. The battery for energizing the release magnet 161 and the upper winding of relay 130 is connected in series with a common supervisory relay not shown. The release magnet operates over the above circuit to permit the minor switch wipers to restore to normal. Relay 130 operates and closes ground to the common supervisory equipment at contacts 131. During the time that the minor switch MS is restoring the selector is guarded by preventing battery through contacts such as U1b and the lower winding of relay 130 from being impressed on the C conductor at contacts 162. When the minor switch has restored completely the latter contacts are closed and contacts 163 open to interrupt the circuit to release magnet 161. At the same time the circuit 75

to the upper winding of relay 130 is opened at wiper W2 permitting it to restore.

In the event that all of the trunks in the "0" group were busy at the time that relay 150 was operated following the termination of the series of impulses received over the calling line, none of the relays U1 to U0 will be operated. When relay 150 operated it closed a circuit from ground through contacts 152, relay 140, and contacts such as U1b on relays U1 to U0 to battery. Relay 140 is made slow to operate by a copper slug on the armature end of its core to enable relays U1 to U0 to operate first if any trunks are idle. After a brief delay relay 140 operates, provided none of the relays U1 to U0 have operated; transfers the lower winding of relay 110 from the dial tone and ground lead DTG to the busy tone and ground lead BTG at contacts 141; opens points in the circuits to magnets 160 and 161 at contacts 142 and 143; closes a circuit from ground, through contacts 144, the lower winding of relay 130, and contacts such as U1b on relays U1 to U0 to battery; locks to ground through contacts 124 at contacts 145; and grounds wiper W1 at contacts 147 to hold relay T0 operated after 130 reoperates. Relay 130 operates and opens the circuit to relay 150 at contacts 132. Relay 150 restores, opens the operating circuit to relay 140 at contacts 152, and disconnects relays U1 to U0 from the control conductors of trunks 01 to 90 at contacts such as 151. When the calling party hangs up in response to the busy signal, relay 110 restores and opens the circuit to relay 120 at contacts 111. Relay 120 subsequently restores, opens the locking circuit to relay 140 at contacts 124, closes ground through these contacts and contacts 146 and T0d to the all trunks busy lead ATB-0 of the "0" groups of trunks, and closes ground through wiper W2 and contacts 125 and 104 to the upper winding of relay 130. Relay 140 restores after a brief delay, closes a previously traced circuit to the minor switch release magnet 161 at contacts 143, opens the circuit to the lower winding of relay 130 at contacts 144, removes ground from lead ATB-0 at contacts 146, and opens the circuit to relay T0 at contacts 147. Relay T0 restores and the minor switch and relay 130 restore in succession as previously described. The momentary ground on the ATB leads may be used to operate peg count meters for traffic study.

In order to facilitate tracing calls, each of the group selecting relays T1 to T0 is provided with contacts such as T0e for connecting lamp 170 to a corresponding one of the leads TL-1 to TL-0. Thus by grounding lead TL-0 the lamps, such as 170, of all selectors switched through to the "0" group of trunks will be illuminated.

While a particular embodiment of the invention has been illustrated, it should be understood that numerous modifications may be made therein without departing from the scope of the invention as defined in the subjoined claims; for example, the minor switch MS may be replaced by a relay type counting chain if desired.

What is claimed is:

1. In a telephone system, a calling line, a plurality of groups of trunks each including a test conductor for marking them busy or idle, a plurality of group selecting relays, a plurality of individual selecting relays, means for selectively operating said group selecting relays in accordance with digital impulses received over the calling line, each of said group selecting relays operative to extend the test conductors of a cor-

5

responding group of said trunks to said individual selecting relays, said individual selecting relays operative to test all of the trunks in the group extended thereto simultaneously and to extend said calling line to an idle one thereof.

2. In a telephone system as claimed in claim 1, time delay means started in operation when any of said group selecting relays are operated and stopped when any of said individual selecting relays are operated, said timing means operated to transmit a busy signal over the calling line in the event that none of said individual selecting relays are operated within a predetermined time interval following the operation of any of said group selecting relays.

3. In an automatic selector switch of the relay type, a plurality of group relays each adapted to establish connections simultaneously with a group of trunk lines, impulse responsive means directly controlled in accordance with a digit in a called number for selecting and energizing one of said group relays to select the associated group of trunk lines, and a plurality of individual trunk selecting relays operative to test all of the trunks in the selected group simultaneously and to establish connection with an idle one thereof in response to the operation of one of said group relays.

4. In a telephone system, a calling line, a plurality of groups of trunks each including a test conductor for marking them busy or idle, a plurality of group selecting relays, a plurality of individual selecting relays, means for selectively operating said group selecting relays in accordance with digital impulses received over the calling line, each of said group selecting relays operative to connect the test conductors of a corresponding group of said trunks to said individual selecting relays, said individual selecting relays operative to test all of the trunks in the group connected thereto simultaneously and to select an idle one thereof, and means responsive to the operation of any of said individual selecting relays for severing said connection of the test conductors of the selected group of trunks to the said individual selecting relays.

5. In an automatic selector switch of the relay type, a plurality of group relays each adapted to establish connections simultaneously with a group of trunk lines, impulse responsive means directly controlled in accordance with a digit in a called number for selecting and energizing one of said group relays to select the associated group of trunk lines, a plurality of individual selecting relays, means operated momentarily upon the selection of a group of trunk lines for connecting the test conductors thereof to said individual selecting relays, said individual selecting relays operated to test all of the trunk lines in the selected group simultaneously and to select an idle one thereof in response to the momentary connection of the test conductors thereto.

6. In an automatic selector switch, a plurality of individual selecting relays, a plurality of group selecting relays each arranged to connect a corresponding group of trunk lines to contacts of said individual selecting relays, a further relay arranged to connect the test conductors of a selected group of trunk lines to windings of said individual selecting relays, means responsive to a series of impulses for selectively operating one of said group relays and for momentarily operating said further relay upon the termination of the series of impulses, said individual selecting relays

6

operative to test all of the trunks in the selected group simultaneously and to select an idle one thereof in response to the concurrent operation of one of said group relays and said further relay.

7. In a telephone system, a calling line, a plurality of groups of trunks each including a test conductor for marking them busy or idle, a chain of relays, means for selectively extending said groups of trunks to said chain of relays in accordance with digital impulses received over the calling line, said chain of relays operative to test the test conductors of all of the trunks in the group extended thereto simultaneously and to extend said calling line to an idle one thereof.

15 8. In a telephone system, a plurality of selectors each having access to a plurality of groups of trunks, a plurality of conductors each corresponding to one of said groups, an indicating means for each selector, means in each of said 20 selectors operated in response to the selection of one of said groups of trunks for connecting the corresponding one of said conductors to the indicating means of the selector, whereby all of the 25 selectors which have selected a given group of trunks may be readily identified by completing a circuit to the conductor corresponding to the given group to energize the indicating means of such selectors.

9. In a telephone system, a calling line, a selector switch, a plurality of groups of trunks each including a test conductor for marking them busy or idle, testing means, means for selectively extending said groups of trunks to said testing means in accordance with digital impulses received by said switch over the calling line, said testing means operative to test the test conductors of all of the trunks in the group extended thereto simultaneously and to cause said calling line to be extended to an idle one thereof.

40 10. In a telephone system, a calling line, a selector switch, a plurality of groups of trunks, a progressively movable device for selecting desired ones of said groups of trunks in accordance with digital impulses received by said switch over the 45 calling line, and testing means operated to test all of the trunks in a selected group simultaneously and to cause said calling line to be extended to an idle one thereof.

11. In a telephone system, a calling line, a plurality of groups of trunks, a test conductor for each trunk, an automatic switch having group and units relays for extending connections, impulse responsive means for selectively operating any one of said group relays to prepare connections to all of the trunks in a selected one of said trunk groups, automatic means for thereupon connecting the test conductors of all of said last named trunks to said units relays to test all of such trunks simultaneously and to energize those units relays connected to idle trunks, and circuits controlled by said units relays to permit the operation of only one of such energized relays to extend a connection from said calling line to an idle trunk in the selected trunk group.
